UNITED STATES PATENT OFFICE

102,950

DESIGN FOR A SCARF

William Karp, New York, N. Y.

Application December 12, 1936, Serial No. 66,493

Term of patent 3½ years

To all whom it may concern:

Be it known that I, William Karp, a citizen of the United States of America, residing in Manhattan, in the county of New York and State of New York, have invented a new, original, and ornamental Design for a Scarf, of which the following is a specification, reference being had to the accompanying drawing, forming part thereof, wherein,

The scarf is of an allover lace, as shown.

I claim:

The ornamental design for a scarf, substantially as shown, and described.

WILLIAM KARP.
